[57] CLAIM

The ornamental design for an air conditioner, as shown and described.

DESCRIPTION

FIG. 1 is a front elevational view of an air conditioner, showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is an enlarged front, bottom and right side perspective view thereof;

FIG. 7 is an enlarged cross-sectional view thereof, taken along line 7—7 of FIG. 1; and,

FIG. 8 is an enlarged front, bottom and right side perspective view thereof, with the louvre opened.

The left side elevational view is omitted as that is symmetrical to the right side elevational view.
